UNITED STATES PATENT OFFICE.

SAMUEL B. WILLIAMS, JR., OF BROOKLYN, NEW YORK, AND RALPH L. QUASS, OF HAWTHORNE, NEW JERSEY, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

1,330,417.

Specification of Letters Patent. Patented Feb. 10, 1920.

Application filed November 13, 1916. Serial No. 131,089.

To all whom it may concern:

Be it known that we, SAMUEL B. WILLIAMS, Jr., and RALPH L. QUASS, citizens of the United States, residing at Brooklyn, in the county of Kings and State of New York, and at Hawthorne, in the county of Passaic and State of New Jersey, respectively, have invented certain new and useful Improvements in Telephone-Exchange Systems, of which the following is a full, clear, concise, and exact description.

This invention relates to telephone exchange systems and more particularly to a system of the call distributing type. Its principal object is to provide a call distributing system having a high degree of flexibility, efficiency and reliability of operation.

In systems of the type to which the present invention relates, it is customary to provide automatic switches for extending the circuits of calling lines to operators' positions where connection with the lines that are called may be completed. In order to afford the highest degree of flexibility and to enable the apparatus to operate at its highest efficiency, it is desirable that each of the subscribers' lines shall have access to all of the operators' positions and that each operator's position shall be accessible from all of the subscribers' lines. But where the exchange is a large one serving a great many subscribers' lines and employing a great many operators' positions, such a result may be difficult to attain on account of the physical limitations of the switches that select and connect with the operators' positions. Furthermore, the throwing together into one electrically inter-related group of all the operators' positions and all the paths over which the lines have access to them, while desirable from the standpoint of flexibility and efficiency, is objectionable on account of the increased possibility of all service being temporarily shut off on account of some accident occurring in the single group that is thus constituted.

In the present invention, the operators' positions and the paths over which they are reached are divided into a plurality of groups. Certain groups of telephone lines normally have access to one group of operators' positions, and other groups of lines

normally have access to another group of operators' positions. But each group of lines is provided with switching appliances which operate, when for any reason the operators' positions to which the group normally has access cannot be reached or cannot give service, to direct the calls to another group of operators' positions. Thus the system of the invention realizes the advantages of flexibility and efficiency that arise from giving each line access to a large number of operators' positions, while retaining those advantages connected with the use of smaller groups, involving the use of simpler switches for reaching the operators' positions and a lessened possibility of the accidental shutting off of service.

The manner in which these results are attained may best be explained by reference to the specific embodiment of the invention illustrated in the accompanying drawings, in which Figure 1 is an isometric view illustrating in skeleton and diagrammatic form the inter-connection of two groups of operators' positions with the line finder frames and cord selector frames of a call distributing system, and in which Figs. 2 to 7 inclusive, when arranged side by side in the manner indicated by the corresponding lines that extend to the margins of the drawings, show diagrammatically a preferred circuit organization of such a system.

Referring first to Fig. 1, this illustrates diagrammatically a number of line finder frames FF-1, FF-2 and FF-3, interconnected by means of finder circuits FC-1, FC-2, etc., with a number of cord selector frames SF-1, SF-2, SF-3 and SF-4, each of the line finder frames FF-1, FF-2, FF-3, serving as the terminal of a plurality of subscribers' lines extending to the frame in the line cables LC-1, LC-2 and LC-3, respectively, and each of the cord selector frames SF-1, SF-2, etc., serving as the terminal of a plurality of connecting cord circuits, the conductors of which are carried in the cables OC-101, OC-102, etc., and OC-201, OC-202, etc., which extend respectively to the various operators' positions of "group 1" and "group 2."

The line finder frames FF-1, FF-2, etc., and the cord selector frames SF-1, SF-2,

etc., with their associated switches, may be of the type which is illustrated in Patent 1,177,044 to James L. McQuarrie, issued March 28, 1916, to which more particular reference will be made hereinafter.

- In the specific embodiment of the invention diagrammatically represented in Fig. 1, each of the line finder frames FF-1, FF-2, etc., may serve as the terminal of five hundred subscribers' lines divided into ten groups of fifty lines each. On each side or face of the line finder frame and coöperating with the five hundred line terminals, which appear on each side or face, there may be thirty elevators or movable switches, each serving as a terminal of an associated finder circuit FC. Each of the cord selector frames SF-1, SF-2, etc., may serve as the terminal of nineteen groups of connecting cord circuits, each group containing the conductors of twenty-five connecting circuits and extending through the cables OC to a different operator's position. On each side or face of each cord selector frame SF there may be thirty elevators or switches, each serving as a terminal of one of the finder circuits FC the other terminal of which is a corresponding elevator on an adjacent line finder frame FF. Thus the five hundred telephone lines which terminate on each line finder frame FF have access by way of thirty finder circuits and the cord selector frame on the right to which they extend to the nineteen operators' positions, in one group, and by way of thirty finder circuits and the cord selector frame on the left to which they extend to the nineteen operators' positions of another group.
- Each line cable LC-1, LC-2, LC-3, etc., carrying the conductors of five hundred lines, terminates upon a different one of the line finder frames FF-1, FF-2, etc., and also extends to multiple springjacks accessible to all of the positions of "group 1" and "group 2". It will be understood, of course, that only enough of the whole equipment is shown to illustrate the scheme of interconnection.
- In outline, referring to Fig. 1, the operation is as follows: When a subscriber calls whose line terminates, for instance, in line finder frame FF-1, the act of taking the telephone receiver from its hook operates the trip magnet TM on finder frame FF-1 corresponding with the group of fifty lines in which the calling subscriber's line is located. It also actuates the starting apparatus SA associated with this line finder frame, and the starting apparatus in operating appropriates one of the finder circuits FC which has been preselected and starts the line finding elevator or switch of that finder circuit hunting for the calling line. If the throw-over apparatus TO associated

with the starting apparatus of the finder frame FF-1 is thrown toward the right, as shown in the drawing, the elevator of one of the finder circuits FC-2 serving the right-hand side of the line finder frame FF-1 is started. If the throw-over apparatus TO is thrown to the left, an elevator associated with one of the finder circuits FC-1 serving the left side of the finder frame FF-1 is started. This is indicated diagrammatically by the connection of the right-hand contact of the throw-over apparatus TO with the finder sequence switches FSS of the right-hand group of finder circuits FC-2, and of the left-hand contact of the throw-over apparatus TO with the finder sequence switches FSS of the left-hand group of finder circuits FC-1.

Assuming that the throw-over switch associated with finder frame FF-1 is in the position shown, one of the finder circuits FC-2 is appropriated and its line finder elevator started and brought into engagement with the terminals of the calling line. When this happens, the finder sequence switch FSS of the finder circuit cooperates with the operator's selecting apparatus OSA of the cord selector frame SF-2 to select an unengaged operator's position of "group 1", start the cord selector elevator of the appropriated finder circuit, trip the set of brushes corresponding with the selected operator's position, and cause the brushes to find the terminals of an idle cord circuit of that position and make connection with them. Assuming that the position selected is position 2 of "group 1," the operator at that position, having communicated with the calling subscriber and learned the number of the line wanted, completes connection with it by inserting the plug of the chosen connecting cord circuit at her position into the springjack of the called subscriber's line.

The normal position of the throw-over apparatus TO associated with line finder frame FF-1 is, as shown, such as to cause the calling lines terminating at that frame to be connected with by the line finder elevators of the finder circuits of group FC-2; and therefore all of the calls originated by the lines terminating on that frame are normally routed to the various operators' positions of "group 1". But, as will hereinafter be explained in detail, the organization of the system is such that if all of the operators of "group 1" are either busy or absent from their positions, or have all of their cord circuits in use, or if all of the finder circuits of group FC-2 are in use, or if the condition of the operator's selecting apparatus OSA of cord selector frame SF-2 is such that the operators' positions reached through that frame cannot be selected, then the throw-over apparatus TO of line finder frame

FF—1 is operated to switch its circuits from the sequence switches of the finder circuits FC—2 to the sequence switches of the finder circuits FC—1. When this happens, all 5 calls originated by the lines terminating in finder frame FF—1 are extended, in the same manner as has already been indicated, by way of the finder circuits FC—1 and the cord selector frame SF—1 to the cord circuits 10 at the various operators' positions of "group 2".

In the case of the five hundred lines of line finder frame FF—1, "group 1" of operators' positions is the preferred group, as 15 that is the group to which the calls are normally routed, and "group 2" of operators' positions is the alternate group. In the case of the five hundred lines terminating in line finder frame FF—2, the calls are 20 normally directed over one of the finder circuits FC—4 and cord selector frame SF—3 to "group 2" of operators' positions, and when the throw-over condition arises are directed by way of the finder circuits FC—3 25 and cord selector frame SF—2 to "group 1" of operators' positions. In the case of the five hundred lines of line finder frame FF—2, therefore, "group 2" is the preferred group, and "group 1" is the alternate group. 30 In the case of the five hundred lines terminating on line finder frame FF—3, the normal condition of the throw-over apparatus, as shown, is such that "group 1" is the preferred group and "group 2" is the alternate 35 group; and in like manner, the entire series of line finder frames may be so controlled by the associated throw-over apparatus as to make "group 1" the preferred group and "group 2" the alternate group in the case 40 of part of them, while the reverse may be the case with respect to the rest of them. Or, as will be described hereinafter, the throw-over apparatus may be so set or manipulated that the calls of all of the lines of the 45 change may be directed into either group of operators' positions to the exclusion of the other group.

Referring now to the specific embodiment of the invention as illustrated in Figs. 2 to 50 7 inclusive of the drawing, this embodiment is represented as comprising telephone lines extending from stations as A and A' to stationary terminals upon the opposite faces or sides of a line finder frame, the right-hand 55 side of the frame being served by a plurality of line finder switches or elevators G and the left-hand side of the frame being served by a plurality of line finder switches or elevators G'. Each line has associated with it 60 a line relay 12 and a cutoff relay 11, and each group of fifty lines on the frame has associated with it certain group apparatus designated as LG and LG'. The group apparatus is connected through the medium of 65 conductors 57 and 58 with the starting and

throw-over apparatus, which apparatus is common to all of the groups and to the five hundred lines terminating upon the line finder frame, and is shown in Fig. 4. This common starting and throw-over apparatus 70 is connected through the medium of the conductors 25, 26, 27, 28, 29, 78, 79 and 80 with the apparatus of the group of finder circuits F, F' and F² associated with the line finder switches or elevators G on one side of the 75 frame, and through the medium of the conductors 25', 26', 27', 28', 29', 78', 79' and 80' with the apparatus of similar finder circuits associated with the line finder elevators or switches G' on the left-hand side of the 80 frame. As the circuits serving the left-hand side of the line finder frame may be understood to be precisely the same as those serving the right-hand side of the frame, they are not shown. The finder circuits F, F', F², 85 etc., terminate in cord selector switches or elevators CS, CS', etc., and through the medium of these, operating under the control of the operator's selecting apparatus SF—4, the finder circuits are adapted to have their 90 connections extended to any one of the connecting cord circuits 85, 86, 87 and 88 at any one of the operators' positions such as are indicated at O and O'. Each one of the connecting cord circuits of the group at each of 95 the operators' positions may be equipped as illustrated, and may terminate in a plug 170 which may be inserted in a multiple spring-jack 14 of a line extending to a called subscriber's station A². The multiple connection 100 of the circuits of the various operators' positions with different cord selector frames, which is shown clearly in Fig. 1 of the drawing, is indicated in the circuit diagram by the stub connections shown at SF—2. These 105 stub connections may be understood to represent connections of the same sort as are shown fully at SF—4 in the circuit diagram.

As heretofore stated, the line finder switches of groups G and G' and the cord 110 selector switches CS and CS' may be substantially like the switch illustrated and described in Patent 1,177,044 to James L. McQuarrie, issued March 28, 1916. The line finder and cord selector switches are alike 115 in all substantial respects. Each comprises a longitudinally movable shaft 1 carrying as many sets of brushes 2 as there are groups of stationary terminals to be engaged. To move the shaft up, an extension at the lower 120 end of the shaft is brought into engagement with the constantly rotating power member 3 by means of an idler wheel operated by the up-drive magnet 32; and to move the shaft down, the extension is brought into 125 engagement with the power member 4 by means of an idler wheel operated by the down-drive magnet 62. Normally the brushes of each of the sets 2 are held apart so as to clear the associated terminals by 130

means of a separating cam 5 located between the innermost brushes of the set. The cam 5 is rotatably mounted, and when rotated in one direction releases the brushes 5 and permits them to engage the associated terminals. The tripping or releasing of the brushes is controlled by a number of trip magnets, as 16 and 17. Each of these when energized rotates an associated trip rod 6 10 that extends transversely to the switch shafts 1 and carries as many trip yokes 7 as there are finder switches in the group. The trip rod in rotating brings all of its trip yokes 7 into position to operate the brush-controlling cams 5 of the corresponding sets of brushes on all of the switches, so that whichever of the finder switches is caused to move up has that set of brushes tripped that corresponds with the particular 15 trip magnet 16, 17, that is at the time energized. When the finder switch that has been in use is returned to its normal position, any of the associated controlling cams 5 that has been tripped is engaged and rotated in a reverse direction to separate its switch springs again and thus render them inactive. Each of the line finder and cord selector switches has associated with it a commutator 8 which comprises a number 20 of stationary commutator segments and a set of movable brushes carried at the top of the switch shaft 1 and coöperating with the stationary segments. This commutator serves to make and break a number of the 25 controlling circuits in the various stages of the upward movement of the switch shaft.

For controlling the circuits of the organization, there are employed a number of 30 sequence switches which are shown at different points and are designated 100, 200 and 300, respectively. These sequence switches may be of the type disclosed in Patent 1,127,808, issued February 9, 1915, 35 to Reynolds and Baldwin. Each consists of an electromagnetically controlled motor or driving mechanism and a number of associated switch cams. The switch cams associated with each of the sequence switches 40 are designated 101 to 103, inclusive; those associated with each of the sequence switches 200 are designated 201 to 222, inclusive; those associated with each of the sequence switches 300 are designated 301 to 45 100 101 to 103, inclusive; those associated with each of the sequence switches 200 are designated 201 to 222, inclusive; those associated with each of the sequence switches 300 are designated 301 to 50 105 106 to 108, inclusive. To each of the contacts associated with the various sequence switch cams are applied certain numerals. These numerals in the case of the cams 101, 201 and 301 indicate the only positions of the associated sequence switch in which these particular contacts are open; the numerals applied to all of the other contacts of each sequence switch indicate the only positions of the particular sequence switch in which 55 110 115 120 125 130 the associated contacts are closed.

The sequence switches 100 merely act as timing switches and have only one resting position. The resting positions of the other sequence switches, and the stages of operation with which these positions are associated, are as follows:

Sequence switch 200.

1. Normal.
2. Awaiting starting circuit.
3. Awaiting starting circuit release.
4. Hunting calling line.
5. Awaiting preceding finder circuit.
6. Awaiting operators' selecting circuit.
7. Releasing operators' selecting circuit.
8. Hunting cord circuit.
9. Talking.
10. Line finder at telltale.
11. Line finder return.
12. Cord selector return.

Sequence switch 300.

1. Awaiting a call.
2. Position vacant.
3. Position busy.

The operation of the system as illustrated in the accompanying drawings is as follows: When a subscriber calls, the taking of the telephone receiver from its hook closes a circuit in the usual way that causes the energization of the associated line relay 12 at the central office. The line relay in operating closes a circuit that extends from battery through the winding of relay 19 of the group in which the calling line is located, 100 contacts 103 (18 $\frac{3}{4}$ to 1 $\frac{1}{4}$) of sequence switch 100 of that group, group conductor 18, and armature and front contact of line relay 12 to ground. Relay 19 in operating closes a circuit that extends from battery through 105 the right-hand winding of relay 24, front contact and armature of relay 19, conductor 57, inner back contact and armature of relay 22, left-hand back contact and armature of relay 23, back contact and armature of relay 65 to ground. Relay 24 in operating closes a locking circuit for itself in its left-hand front contact and armature and in doing so causes the operation of the associated tripping magnet 16, the energizing path for the 110 tripping magnet and for the left-hand or locking winding of the relay 24 being by way of the left-hand front contact and armature of relay 24, conductor 58, winding of relay 22, left-hand armature and back contact of relay 23, and back contact and armature of relay 65 to ground. Relay 24 in operating also closes a circuit that extends from battery through the motor magnet of the associated sequence switch 100, sequence 115 switch contact 102 (18 $\frac{3}{4}$ to 1 $\frac{1}{4}$) and right-hand contact and armature of relay 24 to ground. The closure of this circuit moves sequence switch 100 out of position 1, whereupon the switch continues to rotate, un- 120 125 130

der the control of its governing cam 101, until it completes its cycle and again comes to rest in position 1, the circuit by way of cam 102 (18 $\frac{3}{4}$ to 1 $\frac{1}{4}$) opening in the meantime as a result of the release of the relay 24. While the sequence switch 100 is rotating it maintains open in sequence switch contact 103 (18 $\frac{3}{4}$ to 1 $\frac{1}{4}$) the connection of the relay 19 with the group conductor 18, so that during this period the relay 19 is not under the control of the line relays 12. During this interval the calling line is found and the line relay 12 deenergized to remove the ground from conductor 18, as will hereinafter be described.

Included in the circuit by way of conductor 58 closed upon the initiation of a call, as described above, is the winding of the starting relay 22. This relay in operating closes the circuit of the starting conductor 129, and in doing so brings about the movement of a line finder switch in one or the other of the groups of switches G and G' that have access to the terminals of the five hundred lines in which the line assumed to be calling is located. These two groups are preferably those on opposite sides of the line finder frame; but if desired the switches on one side of the frame may be divided into groups feeding into corresponding groups of operators' positions.

The particular group in which a line finder switch will be started by the operation of the starting relay 22 is dependent upon the condition of energization or deenergization of the relay 66, and upon the direction in which the preference-switch P is thrown, as will be described hereinafter. Assuming that the relay 66 is deenergized and that the preference-switch P is thrown to the right, the starting conductor 129 is connected with the conductor 29 extending to the sequence switch contacts of the finder circuits that terminate upon the line finder switches of group G.

For reasons that will hereinafter be explained, only one of the sequence switches associated with the finder circuits of group G is in position 2. Assuming that this is the sequence switch of finder circuit F, a circuit is completed that extends from battery through the left-hand winding of relay 30, sequence switch contacts 206 (2), conductor 29, right-hand contacts P' of preference-switch P, right-hand back contact and armature of relay 66, conductor 129, inner front contact and armature of relay 22, left-hand armature and back contact of relay 23, and back contact and armature of relay 65 to ground. Relay 30 in operating closes a locking circuit for itself that extends from battery through resistance coil 56, sequence switch contacts 217 (2 to 9), right-hand winding of relay 30, sequence switch contacts 216 (2 to 4) and (2 to 9), left-hand

front contact and armature of relay 30, and armature and back contact of relay 37 to ground. Relay 30 also closes a circuit that extends from battery through the motor magnet and cam 202 (2) of sequence switch 70 200, right-hand front contact and armature of relay 30, sequence switch contacts 208 (18 to 14) and (2 to 7) to ground. The closure of this circuit causes sequence switch 200 to move out of position 2 and come to 75 rest in position 3.

In position 3 of the switch, a circuit is closed that extends from battery by way of the up-drive magnet 32 of the corresponding line finder switch LF', sequence switch contact 207 (3 to 4), front contact and right-hand armature of relay 30, and sequence switch contacts 208 (18 to 14) and (2 to 7) to ground. The energization of the up-drive magnet 32 starts the upward movement of 80 the corresponding elevator rod with its associated sets of brushes. At the outset of the upward movement of the elevator rod, all of the brush trip levers are moved past the corresponding trip yokes. The only trip 90 magnet that is energized in this case is the magnet 16 which corresponds with the group in which the calling line is assumed to be located; and consequently the only trip yoke in position to engage a trip lever on the 95 elevator rod is the one which controls the brushes 40, 41, 42 and 43 that are adapted to engage the terminals of that particular group of lines. This set of brushes, therefore, is released and made operative, and the 100 other sets are held clear of their associated line terminals.

As soon as the set of brushes corresponding with the calling line is tripped, the group apparatus, by means of which the 105 lines control the brush tripping and line finder starting operations, may be returned to its normal condition. The first step in this restoring operation is effected by the closure of a circuit which is completed by 110 way of the K segment of the line finder commutator immediately after the brushes are tripped. This circuit extends from battery in parallel branches through the relays 33 and 23 (see Fig. 4), conductor 126, switch 115 125, spring P⁵ and right-hand contact of the preference switch P, conductor 26, sequence switch contact 209 (2 $\frac{3}{4}$ to 3), conductor 68, and to ground by way of the K segment of the line finder commutator and its associated 120 brush. The energization of the relay 23 interrupts, in the left-hand back contact of that relay, the previously described circuit that has up to this time maintained the energization of the trip magnet 16, the group 125 relay 24 and the common starting relay 22. Relay 23, in its right-hand front contact, closes a locking circuit for itself and the associated relay 33 that extends by way of conductor 125, left-hand armature and back 130

contact of relay 66, switch-spring P^4 and right-hand contact of the preference switch P , conductor 25, and the sequence switch contacts 210 (2 $\frac{1}{4}$ to 1) of all of the finder circuits in series, to ground at a point beyond the last switch of the series.

As has already been stated, normally there is only one of the finder circuits with its sequence switch in position 2 awaiting the receipt of a call. When the call comes in this sequence switch is immediately moved to position 3, in the manner described above. Therefore at this state of the operation the sequence switches of all of the finder circuits, being either in position 1 or in position 3 and beyond, are in position to close their contacts 210. The locking circuit for the relays 23 and 33 is therefore held closed until another one of the finder circuits has its sequence switch moved into position 2 to break the locking circuit in the corresponding sequence switch contacts 210. This is accomplished by relay 33 which in operating applies a ground to conductor 128 to move the sequence switch of another finder circuit out of position 1 and into position 2, and which also applies a ground to the conductor 127 to move the sequence switch of the appropriated finder circuit out of position 3.

Assuming that the sequence switch of finder circuit F' is in position 1, and that the sequence switch of finder circuit F^2 is in some position between 4 and 17, that finder circuit being assumed to be in use, the operation of the relay 33 completes a circuit from battery, through the motor magnet and contacts 203 (1) of the sequence switch of finder circuit F' , contacts 211 (1) of the same sequence switch, contacts 211 (3 to 17) and (4 to 17) of the sequence switch 200 of finder circuit F^2 , contacts 211 (3 to 17) and (3 to 31) of the sequence switch 200 of finder circuit F that has just been appropriated, conductor 28, right-hand contact and switch spring p^7 of preference switch P , conductor 128, and left-hand front contact and armature of relay 33 to ground. This causes the sequence switch of finder circuit F' to move into position 2. At the same time the sequence switch of finder circuit F is moved out of position 3 by the closure of a circuit that extends from battery through the motor magnet and contacts 203 (3) of the sequence switch of that circuit, conductor 27, right-hand contact and switch spring p^6 of preference switch P , and right-hand front contact and armature of relay 33 to ground.

As soon as the sequence switch of finder circuit F' moves into position 2, it opens in its contacts 210 the circuit by way of conductors 25 and 125 which up to this moment has maintained relays 23 and 33 energized, and these relays thereupon re-

lease their armature. Relay 23 in releasing reconnects to ground the circuit which extends in branches 57 and 58 through the various sets of line group relays, thus again giving the line groups access to the starting circuit.

At this stage of the operation of the system the sequence switch of the appropriated finder circuit F is in position 4, and the elevator rod of the associated line finder LF' is moving up with the set of brushes tripped that corresponds with the group in which the calling line is located. As the tripped brushes rise, they come into engagement successively with the sets of terminals corresponding with the different lines of the group. At the instant of engagement of the brush 42 with the corresponding line terminal 46 of each line, a circuit is closed that extends from battery by way of the relay 52, sequence switch contacts 212 (2 to 4), conductor 50, brush 42, line terminal 46, conductor 53, and winding of cut-off relay 11 to ground. In case a line over which the brushes are passing is busy either as a calling or as a called line, a branch path from battery is closed to conductor 53 which serves to shunt the relay 52 and prevent its operation as the finder brushes pass over the terminals of the corresponding line. In the case of the lines that are not busy, the relay 52 is operated as the brushes engage the terminals of such lines. In attracting its armatures, the relay 52 closes a circuit that extends from battery through the lower winding of relay 37, front contact and lower armature of relay 52, sequence switch contacts 213 (2 to 4), conductor 49, brush 41, line terminal 45, conductor 39 to one limb of the telephone line, thence by way of the path controlled in contacts of the substation switchhook to the other limb of the line, conductor 38, terminal 44, brush 40, conductor 48, sequence switch contact 214 (2 to 4), upper armature and front contact of the relay 52, upper winding of the relay 37 to ground. The circuit traced above is not completed until the finder switch brushes engage the terminals of the calling line, for the reason that the calling line is the only line that has its telephone receiver off the hook and at the same time is not connected with either by some other line finder or by a connecting cord calling plug. The completion of this circuit energizes the relay 37 and causes that relay to interrupt in its back contact the circuit by way of the left-hand armature and front contact of the relay 30, sequence switch contacts 216, right-hand winding of relay 30, sequence switch contacts 217, and resistance 56 to battery, which circuit has been holding relay 30 locked up from the moment that the relay was first energized upon the receipt of the call.

5 Relay 30 in releasing its armatures breaks its own locking circuit traced above, and also breaks the previously traced path including sequence switch contacts 208 right-hand front contacts of the relay 30, and sequence switch contacts 207, over which current has been flowing to energize the up-drive magnet 32 of the line finder. Therefore, the operation of the relay 37 upon the 10 finding of the calling line acts to effect the instant deenergization of the up-drive magnet 32 and thus to stop the brushes upon the terminals of the calling line.

When the relay 30 is deenergized, as a 15 result of finding the calling line, it also completes a circuit that extends from battery through the motor magnet and contacts 202 (3 to 4) of the sequence switch 200, right-hand back contact and armature of 20 the relay 30, sequence switch contacts 208 (18 to 14) and (2 to 7), to ground. The closure of this circuit moves the sequence switch out of position 4.

When the sequence switch reaches position 25 4 $\frac{1}{2}$, it closes a path for the flow of current through the cut-off relay 11 of the calling line by way of resistance coil 64, sequence switch contact 212 (4 $\frac{1}{2}$ to 12 $\frac{1}{2}$), conductor 50, brush 42, line terminal 46 and conductor 53. The flow of current in this path 30 operates the cut-off relay 11 to disconnect the line relay 12 from the circuit, and that relay in releasing its armature disconnects ground from the common conductor 18. 35 The disconnection of ground from conductor 18 occurs before the timing sequence switch 100 has completed its cycle of rotation and reconnected conductor 18 with relay 19.

The brushes of the line finder switch are 40 now at rest in engagement with terminals of the calling line, the group starting circuit represented by the conductors 57 and 58 and the associated common relay 22 has been released and is in readiness to respond to another calling line, and the sequence switch 45 of another finder circuit has been moved into position 2, and thus brought into operative relation with the starting conductor 129. The stages of the operation that are next to 50 be described have to do with the selection by the appropriated finder circuit of an idle operator's position and the selection of an idle connecting cord on that position.

When the finder sequence switch 200 55 reaches position 5, it closes a circuit that extends from battery by way of the winding of relay 55 (Fig. 6), conductor 71, and sequence switch contact 218 (5 to 8) to ground. The operation of the relay 55 applies ground to the conductors 81 extending 60 to all of the operators' positions to the connecting circuit terminals of which the cord selector switch of the finder circuit has access. At each of the positions where the operator 65 is at her station and is in readiness

to receive a call the associated relay 91 (see Fig. 7) is inert, and the operator's telephone sequence switch 300 is in its 1 position. Consequently, at each of such positions a circuit is closed that extends from battery, through 70 the winding of associated relay 92, armature and back contact of relay 91, sequence switch contact 304 (1), conductor 81, armature and front contact of relay 55 to ground. The relay 92 of each awaiting position therefore 75 attracts its armature and closes a circuit that extends from battery, through the front contact and armature of the relay 92, to the conductor 82, and thence to ground by way of the windings of relay 77. 80

The finder circuit sequence switch 200 does not stop in position 5, but continues its movement and comes to rest in position 6. Here it awaits the closing of a circuit the completion of which is dependent upon the 85 condition of the other finder circuits of the associated group. This circuit extends from battery through the left-hand winding of the relay 30, contact 219 (6) of the appropriated finder circuit sequence switch, contacts 219 (9 to 4) of the sequence switches of the associated finder circuits preceding it in the series, conductor 76, outer armature and back contact of relay 54, and right-hand back contact and armature of relay 61 90 to ground. This circuit is open either in cam 219 of a preceding finder sequence switch 200 in the series or in contacts of the relays 54 or 61 as long as any other sequence switch of the series is in positions 4 to 9. 100 That is, it is open from the time the line finder switch of any associated finder circuit finds a calling line until the cord finder switch of that circuit has moved far enough to trip the brushes corresponding with the 105 selected group. Not until this has occurred will the above traced circuit of the awaiting finder circuit be closed.

The closure of this circuit causes relay 30 to attract its armatures and complete a circuit that extends from battery through the motor magnet and sequence switch contact 202 (6) of the sequence switch 200, front contact and right-hand armature of relay 30, and sequence switch contacts 208 (18 to 14) and (2 to 7) to ground. The completion of this circuit moves the finder sequence switch out of position 6. 110

When the finder sequence switch reaches position 6 $\frac{1}{2}$, it closes a circuit that extends 120 from battery through the winding of relay 54 (see Fig. 6), left-hand back contact and armature of relay 61, conductor 73, and finder sequence switch contact 218 (6 $\frac{1}{2}$ to 8) to ground. Relay 54 attracts its armature 125 and completes a branch of the circuit traced above, which extends from conductor 73 by way of the armature and back contact of the relay 63, front contact and inner armature of relay 54, armature and front contact 130

of relay 77 (which relay is energized, as previously described, as a result of the corresponding operator's position being in readiness to receive a call), right-hand back contact and switch spring of relay 93 of the corresponding group, winding of associated relay 94, winding of relay 93, left-hand switch spring and resting contact of relay 93, conductor 83, left-hand back contact and 5 armature of relay 95 at the O operator's position to battery. Upon the closure of the above traced branch circuit the group relays 93 and 94 are energized in parallel with the relay 54. Relay 93 in operating disconnects its own energizing winding and 10 that of relay 94 from the previously-traced path to battery by way of the left-hand back contact and armature of the relay 95, and connects them in a path which extends from 15 battery by way of the winding of the relay 95 and conductor 84. This causes the relay 95 also to be energized and to interrupt in its left-hand armature and back contact the path by way of conductor 83 over which 20 the relays 93 and 94 were initially energized. 25

Relay 94 in operating closes a circuit from battery through the winding of the trip magnet 20 corresponding to the selected operator's position and to ground by way of the right-hand armature and front contact of the relay 94. This relay also closes a circuit that extends from battery through the winding of the relay 63 and the left-hand 30 armature and front contact of the relay 94 to ground. The relay 63 in operating closes a branch that extends from the conductor 73 (grounded at contact 218 (6 $\frac{3}{4}$ to 8) of the line finder sequence switch) through the 35 armature and front contact of relay 63, conductor 72, sequence switch contact 220 (7), and left-hand winding of relay 30 to battery. Relay 30 attracts its armatures and 40 closes a circuit that extends from battery through the motor magnet and sequence switch contact 202 (7), front contact and right-hand armature of relay 30, sequence switch contacts 208 (18 to 14) and (2 to 7), and thence to ground. The closure of 45 this circuit moves sequence switch 200 out of position 7. Furthermore, relay 30 in operating is locked up over a circuit that extends from battery through resistance 56, sequence switch contacts 217 (2 to 9), right-hand winding of relay 30, sequence switch contacts 216 (7 to 9) and (2 to 9), front contact and left-hand armature of relay 30 and armature and back contact of relay 37 to 50 ground. 55

When the sequence switch reaches position 8 it closes a circuit that starts the upward movement of the brush-carrying rod of the cord finder switch, this circuit extending from battery through the up-drive magnet 60 34 of the cord finder, conductor 89, sequence

switch contact 207 (8 to 9), right-hand front contact and armature of relay 30, sequence switch contact 218 (8 to 9) and thence to ground. At the outset of the upward movement of the cord finder brush rod the tripping levers of the various sets of brushes are brought simultaneously into operative position with respect to the corresponding tripping yokes, and that set of brushes is tripped and made operative whose trip magnet is at the time energized. In the present instance, it is assumed that this is the trip magnet 20 associated with the terminals of the group of connecting cord circuits extending to the O operator's position. 70 75

Immediately after the set of brushes is tripped, the common operator's selecting circuit is restored so as to be available for the use of other cord finder switches. This is effected through the medium of a circuit 80 that is completed by the grounding of the K segment of the cord finder commutator, this segment being so located as to be engaged by its brush immediately after the tripping levers of the sets of brushes pass 85 the associated tripping yokes. The circuit referred to extends from battery, through the winding of relay 61, conductor 74, sequence switch contact 221 (7 $\frac{3}{4}$ to 8), conductor 180, cord finder commutator segment K and its corresponding brush to 90 ground. Relay 61 in operating opens in its left-hand back contact the previously traced circuit by way of conductor 73 which, up to this time, has been holding energized the 95 relay 95 at the O operator's position and the relays 93 and 94 corresponding to this position on the cord finder frame. The release of the relay 94 deenergizes the corresponding trip magnet 20 and the common 100 relay 63. The deenergization of the relay 93 reestablishes, subject to the release of relay 61, the control of other finder circuits over the brush-tripping mechanism of the 105 associated cord finder frame. 110

Relay 61 in operating closes a locking circuit for itself by way of conductor 73, sequence switch contact 218 (6 $\frac{3}{4}$ to 8), and thence to ground. It also completes a circuit that extends from battery through the 115 motor magnet and contact 205 (8) of the sequence switch 200, conductor 75, right-hand front contact and armature of relay 61 to ground. The closure of this circuit moves sequence switch 200 out of position 8. In 120 moving out of position 8, the sequence switch opens its contacts 218 (6 $\frac{3}{4}$ to 8) and 221 (7 $\frac{3}{4}$ to 8), thus deenergizing relay 61 and again extending conductor 73 to the relay 54 and the conductors over which the 125 operator's selection is effected. In closing its right-hand back contact upon release, relay 61 also restores the continuity of conductor 76 and makes it available for moving out of position 6 the sequence switch of 130

some other finder circuit which may be waiting for access to the operator's selecting circuit.

- When the sequence switch 200 is moved 5 out of position 8, it moves into position 9 and there awaits the finding of an idle connecting cord circuit upon the operator's position that has been selected. As the brush-carrying rod moves up, the brushes 111, 112, 113 and 114 of the set that has been tripped come into engagement with sets of terminals 115, 116, 117 and 118 corresponding with the different connecting cord circuits located at that operator's position.
- 10 When a cord circuit is not in use, its corresponding terminal 118 is connected directly to ground; and when the terminals of such a connecting circuit are encountered, a path is completed that extends from battery, through the lower winding of relay 37, sequence switch contacts 206 (8 to 9), conductor 99, brush 114, terminal 118, conductor 88 of the cord circuit, contact 161, which is closed when the associated cord is not in use, and right-hand back contact and armature of relay 119 to ground. Current flowing in this circuit causes the relay 37 to attract its armature and break the previously-traced circuit by way of sequence switch contacts 216 and 217 and the right-hand winding of relay 30 which, up to this time, has been holding relay 30 energized. When the relay 30 is released it opens, in its right-hand front contact, the previously-traced circuit including the up-drive magnet 34, and thus causes the brushes of the cord finder switch to come to rest on the terminals of the selected cord circuit. The relay 30 in releasing also closes a circuit that extends 40 from battery through the motor magnet and contact 202 (9) of the sequence switch 200, back contact and right-hand armature of relay 30, and sequence switch contact 218 (8 to 9) to ground. The closure of this circuit moves the sequence switch 200 out of position 9, whereupon it moves under the control of its contact 201 into position 14, which is the talking position of the finder circuit.
- 45 The connecting circuit to which the finder circuit is thus extended is illustrated in the present instance as being a cord circuit terminating in a connecting plug 170 and including in its talking conductors 85 and 55 86 the windings of a repeating coil 159 with a bridged battery, and the usual signal controlling relays 171 and 187. The connecting circuit also includes a ringing key 120 by means of which current from the ringing 60 generator 181 may be applied to the circuit of the called line, and a listening key 130 by means of which the connection of the operator's telephone 147 with the called line may be controlled.
- 65 The extension of the finder circuit to the connecting cord brings about, in a manner which need not be described, the actuation of a signal on the associated operator's position which informs the operator that a call is waiting. The operator's telephone 70 is connected with the circuit by means of the listening key 130; and when the operator has learned the number of the line with which the calling subscriber desires connection, she completes the connection by inserting the calling plug 170 into the spring-jack 14 of that line. Before the plug is inserted, the usual busy test may be made over the path that is shown extending from the tip of the plug by way of the armature 75 and back contact of the relay 175. When the plug is inserted, a circuit is closed that extends from battery through the winding of the relay 119, winding of the relay 175, the coöperating sleeve contacts of the calling 80 plug 170 and spring-jack 14, and the winding of the cut-off relay 11 to ground. The completion of this circuit causes all three relays to attract their armatures, the relay 119 opening the path to ground of conductor 85, thus rendering the connecting cord circuit unselectable, relay 175 disconnecting the tip of the plug 170 from the test conductor and completing the talking circuit of the tip strand, and the cut-off relay 11 95 disconnecting the line relay 12 of the called subscriber's line. Ringing current from the ringing generator 181 may then be applied to the called subscriber's line by closing the contacts of the ringing key 120.
- 100 By means of appropriate mechanism, which is disclosed in the patent to S. B. Williams, Jr., No. 1,304,641, issued May 27, 1919, (Serial No. 180,634, filed July 14, 1917), and which it is unnecessary to describe, as it forms no part of the present invention, the extension of the finder circuit to the connecting circuit brings about the opening of the contacts of the switch 161 and the closing of the contacts of the switch 152. The switch 152 corresponds to the left-hand armature and front contact of relay 152 of the above mentioned Williams patent, and the switch 161 corresponds to cam 404 of the sequence switch 400 of the 110 Williams patent. The switch 161 in opening its contacts renders the associated cord circuit unselectable immediately and in advance of the opening of the contacts controlled by the relay 119. The closing of the 115 contacts of switch 152 completes a circuit that extends from battery through the winding of relay 155, switch contacts 152, conductor 87, contact 117 and coöperating brush 113 of the cord selector, conductor 120 98, contacts 217 (9 $\frac{1}{4}$ to 14) and (12 to 14) of the finder sequence switch, right-hand winding of relay 30, sequence switch contact 212 (12 $\frac{3}{4}$ to 14), conductor 50, brush 42 and contact 46 of the line finder, conductor 130

53 and winding of cut-off relay 11 of the calling subscriber's line to ground. The current that flows in this circuit keeps the relays 155, 30 and 11 energized during the 5 time that the connection is established. The relay 155 closes a normal break in the ring strand 86 of the talking circuit. The relay 30, as long as it is energized, prevents the finder sequence switch 200 from 10 moving out of its talking position 14. The cut-off relay 11 keeps the branch by way of the line relay 12 disconnected from the calling line.

At the termination of the conversation 15 the replacing of the telephone receivers on their switchhooks at the calling and called subscribers' stations brings about the display of supervisory signals (not shown) controlled by the cord circuit relays 171 and 20 187 in the usual way, and the operator in response to this indication withdraws the calling plug 170 from the spring-jack of the called subscriber's line. The withdrawal of the plug is accompanied by the opening of 25 the contacts of switch 152. This opens the circuit traced in the preceding paragraph including the relays 155, 30 and 11, and these relays release their armatures. When relay 30 of the finder circuit releases it 30 closes a circuit that extends from battery through the motor magnet and contact 202 (8 to 14) of the finder sequence switch, left-hand back contact and armature of relay 30, and armature and back contact of relay 37 35 to ground. This moves the finder sequence switch out of the talking position 14. When the finder sequence switch reaches position 15 it is moved through that position by means of a circuit that is completed from battery, through its motor magnet and contact 202 (15), right-hand back contact and armature of relay 30, sequence switch contacts 218 (15) to ground. When the line 40 finder sequence switch reaches position 16 45 a circuit is completed that extends from battery through the down-drive magnet 62 of the line finder switch, and sequence switch contacts 208 (16) to ground. As a result, the brushes of the line finder switch 50 are returned to normal.

When the brushes reach their normal position, a circuit is closed that extends from battery, through the motor magnet and contact 205 (16) of the finder sequence 55 switch, conductor 69, segment Y of the line finder commutator and its corresponding brush to ground. This moves the finder sequence switch out of position 16. In the next resting position 17 of the finder sequence switch a circuit is closed that extends from battery through the down-drive magnet 35 of the cord selector switch, conductor 90, and sequence switch contact 218 (17) to ground. The closure of this circuit

energizes the down-drive magnet 35 and causes the cord selector brushes to return to their normal position. At the end of the downward movement of the brushes, a circuit is closed that extends from battery through the motor magnet and contact 205 (17) of the finder sequence switch, conductor 31, Y segment of the cord selector commutator and corresponding brush to ground. The completion of this circuit moves the finder sequence switch 200 out 70 of position 17, after which it returns to position 1 under the control of its cam 201.

The operation that has been described in the foregoing is under the assumption that the preference switch P is thrown to the right, as illustrated in the drawing, and that the apparatus and circuits comprised in the group with which the starting circuit is connected under this assumption are in condition to care for the calls that the subscribers' lines initiate. The description will now be directed toward the organization whereby the calls that are initiated are automatically directed to the alternative group of apparatus and circuits in case the preferred group is for any reason incapable of 85 serving the calling lines.

As the foregoing detailed description of the operation of the system has shown, it is through the medium of the group of conductors 125, 126, 127, 128 and 129 that the calling lines exercise their control over the starting of the finder switches and the finder circuits exercise a reciprocal control over the starting apparatus common to the group 95 of telephone lines. It is this group of conductors for the switching of which provision is made in the present organization in order to give the associated group of subscribers' lines control over the finder circuits extending to one or another of two groups of operators' positions.

The apparatus for accomplishing this result comprises a preference switch P which may be manually operated, and an automatic throw-over relay 66 controlled through the medium of groups of relays responsive to various conditions which may arise in the corresponding groups of circuits with which they are associated, in a manner which will 110 be described. The manual preference switch P determines by the direction in which it is thrown the particular group of operators' positions to which the calls of the associated group of subscribers' lines are directed normally. If its switch levers are thrown to the right the calls are normally routed to the operators' positions to which the finder circuits associated with the line finders of group G have access. If the levers of the preference switch P are thrown to the left, the calls are normally routed to the group of operators' positions to which 115 120 125

- the finder circuits associated with the line finders of group G' on the other side of the frame have access. As soon as the throw-over relay 66 is energized, such calls as are initiated during the continuance of this condition are diverted from the operators' position associated with the preferred group and are directed to the operators' positions in the non-preferred or alternate group.
- 10 The energization of the throw-over relay 66 is brought about by the operation of either one of the relays 136 and 138. These two relays are operatively associated respectively with the two groups of circuits over 15 which the calls are adapted to be extended alternatively to the two groups of operators' positions. When the particular one of these relays is operated that is associated with the group which is at the time the preferred 20 group, the throw-over relay 66, subject to certain conditions, is energized to route subsequent calls to the non-preferred or alternate group.

Assuming that the preference switch P is thrown to the right, making the group served by the line finders G the preferred group, when the corresponding relay 138 is operated a circuit is completed that extends from battery through the winding of relay 149, closed contacts s^8 of the switch S, upper front contact and armature of relay 138, and right-hand contact and switch spring p^8 of the preference switch P to ground. If the starting relay 22 is not in its operated condition at this time, relay 149 in operating closes a circuit that extends in two branches from battery to the switch spring of relay 150, one of these branches including the winding of the relay 150, and the other including the winding of the throw-over relay 66 and closed contacts s^2 of the switch S; the circuit thence extending by way of the resting contact of relay 150, closed contacts s^3 of the switch S, right-hand armature and front contact of relay 149, and back contact and armature of the starting relay 22 to ground. The throw-over relay 66, in attracting its armatures disconnects the starting wire 129 and the associated locking wire 125 from conductors 29 and 25, respectively, of the preferred group and connects them with conductors 29' and 25' of the alternate group by way of switch springs p^2 and p^3 and corresponding right-hand contacts of 55 the preference switch P. Consequently such calls as may be initiated thereafter, and while this condition continues, cause the starting of line finders of the alternate group G', and are therefore extended to the 60 cord circuits of the other group of operators in the same manner as that which has hereinbefore been described in detail.

If it is desired that the calls be normally directed to the operators' positions served

by the finder circuits of the group G' of line 65 finders, then the preference switch P will normally stand with its switch levers thrown to the left. With the preference switch P in this position, the conductors 125, 126, 127, 128 and 129 are extended to conductors 25', 70 26', 27', 28' and 29', respectively, and ground is disconnected from the upper armature of relay 138 and connected with the upper armature of relay 136, thus making relay 136 effective to control the throw-over operation 75 in the same way as described for the relay 138.

In this case when the throw-over condition arises the relay 136 in operating causes the operation of the throw-over relay 66, 80 and the relay 66 in attracting its armatures disconnects the starting wire 129 and locking wire 125 from conductors 29' and 25' of the left-hand group and connects them with conductors 29 and 25, respectively, of the right-hand group. Consequently, such calls as are initiated during the continuance of this condition are directed to the group of operators served by the finder circuits which terminate in the 90 line finder switches of group G.

The circuit organization is such that as long as the starting relay 22 is energized, the throw-over relay 66 is prevented either from throwing over from the preferred to 95 the alternate group, or throwing back from the alternate to the preferred group. If when the throw-over condition arises, the starting relay 22 is energized, the previously-described circuit, by means of which 100 the throw-over relay 66 and the relay 150 are energized, is open in the outer back contact and armature of the relay 22. Consequently neither of these relays can be operated until the starting relay 22 is released 105 by the starting of the line finder switch in the manner previously described.

The preventing of the relay 66 from throwing back from the alternate to the preferred group while the starting relay 22 is 110 energized is accomplished through the medium of the relay 151. During the time that the starting relay 22 is energized, it completes a circuit that extends from battery, through the winding of the relay 151 115 and the outer front contact and armature of the relay 22 to ground. The consequent energization of the relay 151 maintains a ground connection in parallel with the ground connection that is kept on the throw-over energizing circuit by way of the front contact and left-hand armature of the relay 149. Consequently, if while the starting relay 22 is actuated the relay 149 is released 120 as a result of the deenergization of the relay 136 or 138, as the case may be, the throw-over relay 66 and the relay 150 are 125 still held energized by the ground applied

by the relay 151. Consequently, the starting wire 129 and the locking wire 125 are not shifted back from the alternate to the preferred group until after the starting relay 22 is released.

The object of the above described provision is to prevent the possibility of the throwing-over or throwing-back operation starting a line finder in each of the two groups in response to the same call. As previously described, the operation of the starting relay 22 causes the instant locking up of the relay 30 of the finder circuit (see Fig. 5), and this relay starts the associated sequence switch and line finder and remains locked up until the line finder engages the terminals of a calling line. If the throw-over relay 66 should either be operated or released an instant after a finder circuit relay 30 of the group with which it was at the time connected was operated, the same ground applied to starting wire 129 in the inner front contact of the relay 22 would operate to lock up a finder circuit relay 30 and start a finder switch of the other group. By holding the throw-over relay 66 either energized or deenergized, as the case may be, as long as the starting relay 22 is energized, this splitting of the start is prevented. The relay 151 is preferably adjusted to act somewhat more quickly than the finder circuit relay 30, in order that when the starting relay 22 operates the relay 151 may be actuated to insure the throw-over relay 66 against releasing before the relay 30 operates to start a finder switch.

Provision is also made for holding up the calls which may be initiated during the time when neither of the two groups of operators is in condition to attend to them. The unavailability of each group is indicated by the actuation of the associated relays 136 and 138. When both of the groups are incapable of attending to calls, both of these relays are energized and a circuit is completed that extends from battery, through the winding of relay 139, lower armature and front contact of relay 136, front contact and lower armature of relay 138 to ground. The relay 139 in operating closes a circuit that extends from battery through the winding of relay 65 and the back contact and outer armature of starting relay 22 to ground. Relay 139 also closes a circuit that extends from battery through the winding of the slow-releasing relay 140 to ground. Relay 140 in operating closes a path from battery for energizing the relay 65 in parallel with the path closed by relay 139. When the relay 65 operates, it closes in its front contact a path to ground for the continued energization of the relay independent of the path by way of the back contact and armature of relay 22. It also opens the ground connection upon which the starting and trip-

ping circuits and relays are dependent for their energization. Consequently, as long as both of the relays 136 and 138 are energized, the operation of the relays 19 of the various subscribers' line groups is ineffective to cause the operation of the corresponding trip magnets and the starting of a line finder switch.

When the circuits of one or another of the groups of operators again become available for extending connections, the release of the corresponding relay 136 or 138 opens the previously-traced circuit including the relay 65, and that relay in releasing restores the control of the starting relay and the trip magnets to the calling lines. Assuming that the right-hand group G is the preferred group and that it is this group that first becomes available for handling calls, the deenergization of the relay 138 not only brings about the restoration of the starting circuit by the release of relay 65, but it also causes the throw-over relay 66 to throw back from the alternate to the preferred group by the release of the relay 149. It is desirable that the release of the relay 65 shall be delayed until after the release of the relay 66 in order that the starting conductor 129 may not be closed by a waiting call until after the switching of the starting wire from the alternate group to the preferred group has taken place. This result is accomplished by the provision of relay 140, which, on account of being slow in releasing, keeps battery applied for the energization of the relay 65 for an interval after the release of the relay 138, acting through the medium of relay 149, has caused the release of the throw-over relay 66.

It will be noted that the energizing circuit of the call-blocking relay 65 is controlled in normally closed contacts of the starting relay 22. This is for the purpose of preventing the relay 65 from being energized to release the relay 22 and the trip magnet connected in circuit with it prematurely in case the condition that is adapted to cause the energization of the relay 65 arises during a time when the starting circuit is closed.

The conditions which are effective through the medium of the relays 136 and 138 in bringing about the throw-over and call-blocking actions set forth in the foregoing will now be described. One of the circumstances which renders a group of circuits unavailable for handling the calls that are initiated is that in which all of the finder circuits feeding into that particular group are in use. When this condition exists, a circuit is completed that extends from battery through the winding of the relay 135 (see Fig. 4), conductor 80 and sequence switch contacts 215 (4 to 17) of all of the finder sequence switches in series to ground.

The operation of relay 135 closes a circuit which extends from battery through the winding of the relay 133 and the front contact and armature of relay 135 to ground; and the relay 133 in turn closes a circuit that extends from battery through the winding of relay 138 and the front contact and armature of relay 133 to ground. This operates the relay 138 and, assuming the 10 associated group to be the preferred group, brings about the results which have previously been described.

Another one of the circumstances which causes the relay 136 or 138 of the associated 15 group to operate to establish the throw-over condition is that in which all of the operators' positions of the associated group are either vacant or actually busy. When this condition exists, a circuit is completed that 20 extends from battery through the winding of the relay 134 (see Fig. 4), conductor 79, and serially by way of a closed one of two normally open parallel paths at each operator's position of the group, to ground at 25 the end of the series. One of these parallel paths at each operator's position (see Fig. 7) includes the front contact and armature of relay 193, and the other includes sequence switch contacts 305 (4). When the operator's position is vacant, the switch levers of 30 the switch 122 are resting against their outer contacts, and a circuit is adapted to be completed from battery through the motor magnet and contacts 303 (1 and 17) of the operator's telephone sequence switch, outer contact and left-hand switch spring of the switch 122 to ground. This circuit prevents the sequence switch from resting in any other position than position 4, and in 35 position 4 the sequence switch contacts 305 (4) above referred to are closed. Consequently, if all operators' positions of the group are vacant, the circuit for energizing the relay 134 is completed through the series 40 of closed sequence switch cams 305, and the relay 134 operates to close the energizing circuit for the relay 138.

If the operator's position is not vacant the sequence switch contacts 305 (4) are 50 open, and the continuity of the conductor 79 is under the control of the contacts of the relay 193. If the operator is listening in on any one of the connecting cord circuits of her position, the switch 415 of that cord circuit is closed in any suitable manner, and a circuit is completed that extends from battery through the winding of relay 193, conductor 137, and to ground by way of the closed contacts of switch 415, the relay 193 55 thus being operated to close the normal break at this position in the conductor 79. Associated with each connecting cord circuit are contacts 416 which are closed in any desired manner when the connection over that

cord circuit is established. When all of the 65 cord circuits of the operator's position are in use, a circuit is completed that extends from battery, through the winding of the relay 194, conductor 148, and to ground by way of the closed contacts 416 of the series of 70 cord circuits. The completion of this circuit energizes relay 194 which thereupon closes a circuit that extends from battery through the winding of relay 193, conductor 137 and front contact and armature of relay 194 to ground, thus energizing relay 193. Consequently, whenever the operator's position is vacant, or whenever the position is occupied and the operator either has her telephone connected with one of the cord circuits or all of the cord circuits of the position in use, the normal break in the conductor 79 at this position is closed; and when one or another of these conditions exists at 75 all of the operators' positions of the group, the path over conductor 79 is completed and the relay 134 is energized to actuate relay 138 as described.

Another circumstance which brings about the energization of one or another of the relays 136 or 138 is the failure of the common operator's selecting circuit of the corresponding group to function properly. It will be remembered that the finder sequence switch 200 is moved out of position 4 when the line finder brushes engage the terminals of the calling line; that the sequence switch waits in position 6, the next resting position, until the circuit of conductor 76 to ground is closed by the completion of the operator-selecting operation of some other finder circuit of the group; that the finder sequence switch is moved out of the next resting position, 7, by the setting of the trip magnet 20 or 21 of the selected operator's position; and that it 90 is moved out of the next resting position, 8, by the grounding of the K segment of the cord selector commutator as the elevator in rising completes the tripping of the selected brushes. The advance of the finder sequence switch 200 from position 4 to position 9 is 95 unattended by any considerable delay if the apparatus is functioning properly. If the advance is delayed to an extent which indicates that the apparatus is not operating 100 properly, it is desirable, as this apparatus is common to all of the finder circuits of the particular group, to divert the calls from this group and route them into the other group.

Normally the sequence switches 200 of all 105 of the finder circuits are in one or another of the positions 9 to 4, and a circuit is completed that extends from battery, through the winding of the slow releasing relay 160, conductor 70, sequence switch contacts 219 (9 to 4) of all of the finder sequence switches 110 in series, conductor 76, outer armature and back contact of relay 54, and right-hand 115

back contact and armature of relay 61 to ground. The relay 160 is therefore normally maintained energized. When one of the finder sequence switches reaches the stage in 5 which the operator's position is to be selected, in moving out of position 4, it opens in its sequence switch contacts 219 (9 to 4) the circuit just traced. This breaks the energizing circuit of relay 160. But if the 10 apparatus is operating properly, before the slow-acting relay 160 has time to release its armatures a circuit is completed for maintaining its energization by way of the left-hand armature and front contact of relay 168 and the outer armature and front contact of relay 55 to ground. The relay 55 has had its energizing circuit closed from the time 15 the finder sequence switch reached position 5, and the energizing circuit of the relay 168 is closed by way of conductor 73 and sequence switch contacts 218 (6 $\frac{1}{2}$ to 8) when the finder sequence switch 200 moves out of its waiting position 6. If there should be any improper delay in the completion of this alternative holding circuit for the relay 160 after 20 the sequence switch of the seeking finder circuit moves out of position 4, the relay 160 would release its armature and would close a circuit from battery by way of the right-hand winding of relay 167 and the back contact 25 and switch spring of relay 160 to ground. In such case the operation of relay 167 closes a circuit that extends from battery through the winding of relay 133 (see 30 Fig. 4), conductor 78, and the front contact and armature of relay 167 to ground, thus energizing relay 133 and causing the operation of relay 138 as described. Likewise, the same result would follow if relay 160 35 should release its armature as a result of an accidental and continuous break in the continuity of its normal energizing circuit by way of conductor 70, the series of sequence switch cams 219, conductor 76, and the rest- 40 ing contacts of relays 54 and 61.

As described above, the advance without undue delay of the finder sequence switch from position 4 to position 6 $\frac{1}{2}$ prevents the relay 160 from releasing its armature to close 45 the energizing circuit of the relay 167. If after reaching position 6 $\frac{1}{2}$ the sequence switch delays too long in positions 6 $\frac{1}{2}$ to 8, a circuit is closed that causes the operation of relay 133 and the diverting of calls from the associated group. When the relay 168 operates as 50 a result of the closure of its energizing circuit in sequence switch contacts 218 (6 $\frac{1}{2}$ to 8), it closes a circuit which extends from battery through the winding of relay 169, 55 and the right-hand front contact and armature of relay 168 to ground. The relay 169 is made especially slow in attracting its armature and may, if desired, be a group of relays organized to accomplish this result 60 in the manner disclosed in Patent 1,163,896 65

to Darrah, issued December 14, 1915. If, therefore, the relay 168 remains energized for an interval longer than that required for the relay, or collection of relays, 169 to operate, a circuit is closed that extends from 70 battery through the left-hand winding of relay 167, armature and front contact of relay 169 and right-hand front contact and armature of relay 168 to ground. Relay 167 is thereupon energized and closes a circuit 75 that extends from battery through the winding of relay 133, conductor 78, and front contact and armature of relay 167 to ground. This actuates relay 133, which in turn brings about the operation of relay 138 to control 80 the throw-over apparatus in the manner described.

In connection with the throw-over apparatus, there is provided a single group-key S, the function of which is to render the 85 automatic throw-over apparatus inoperative and electrically separate the two groups so that either group may be thrown out of service while the other group continues to handle the calls. When the single group-key S 90 is operated, it interrupts in its contacts s^8 the energizing path for the relay 149, thus depriving the relays 136 and 138 of control over the relay 149. It also interrupts in its switch contacts s^1 , s^2 , and s^3 the circuits 95 through the medium of which the relay 150 and the throw-over relay 66 are controlled. In its switch contacts s^4 , s^5 , and s^6 , it interrupts the connections that normally exist between the pairs of conductors 26 and 26', 100 27 and 27', and 28 and 28', respectively, and in its contacts s^7 it closes a circuit which gives the switch contacts p^9 of the group reversing key P control over those switch contacts of the relays 136 and 138 that govern 105 the operation of the call-blocking devices.

With respect to the last-mentioned circuit, if when the single group-key S is thrown, the group reversing or preference switch P has its switch levers thrown to the right, a 110 conducting path is completed that short-circuits the lower contacts of the relay 136, this path extending from the conductor which joins the lower front contacts of the relays 136 and 138, by way of the contact 115 and switch lever s^7 of the single-group key, the lever p^9 and right-hand contact of the preference switch P to the lower armature of the relay 136. When the preference switch P has its levers thrown to the left, the throwing of the single-group key S closes a conducting path that extends from the conductor uniting the lower front contacts of the relays 136 and 138, by way of closed contacts s^7 of the single-group key S, and switch 120 lever p^9 and left-hand contact of the preference switch to ground. As the lower armature of relay 138 is also connected to ground, the closing of this path short-circuits the lower contacts of that relay. 125

The effect in each case is to place the relay 139 exclusively under the control of the contacts of whichever of the relays 136 and 138 is associated with the group which is at the 5 time in service,—as determined by the direction in which the levers of the preference switch P are thrown. As it is the relay 139 and its associated relay 140 that control the call-blocking relay 65, the condition created by the throwing of the single-group key is such that the relay 65 is operated to block the calls whenever the relay 136 or 138 10 of the group that is in service is operated.

In order that the features to which this 15 invention is directed may be fully and clearly disclosed, it has been necessary to describe them in connection with other features that are the subject of co-pending applications assigned to the same assignee, such applications including the application of S. B. Williams, Jr., Serial No. 75,328, filed January 31, 1916, application of S. B. Williams, Jr., Serial No. 75,329, filed January 31, 1916, application of S. B. Williams, Jr., Serial 20 No. 107,090, filed July 1, 1916 and application Serial No. 107,540, filed July 5, 1916 to F. A. Stearn. Such other features are the subject of claims in the applications mentioned above, and are not claimed in the 25 present application.

What is claimed is:

1. The combination with a plurality of telephone lines, of a plurality of groups of 30 operators' positions, a corresponding plurality of finder switches for extending said telephone lines to associated groups of operators' positions, an automatic switch for normally directing calls into one of said groups of positions, and means responsive 35 to a certain condition of said group for operating said automatic switch to direct calls to another of said groups.

2. The combination with a plurality of telephone lines, of two groups of finder 40 switches for making connection therewith, means for moving said finder switches, a starting conductor for each group for controlling the switch moving means of the group, and a device for bringing said telephone lines into operative relation alternatively with one or the other of said starting conductors.

3. The combination with a plurality of telephone lines, of a group of finder switches 45 for making connection therewith, means for moving said finder switches, a starting conductor with which the moving means of the various finder switches are adapted to be brought successively into operative relation, 50 said starting conductor being normally in operative relation with said telephone lines, and means operated when all of the finder switches of said group are in use for discontinuing the operative relation between the 55 lines and the starting conductor.

4. The combination with a plurality of telephone lines, of a plurality of operators' 60 positions divided into groups, a corresponding plurality of groups of finder switches for extending the connections of calling 70 lines to the associated group of operators' positions, one of said groups of finder switches being normally in operative relation with said lines, and means responsive to the busy condition of all of the finder 75 switches of said group for bringing another group of finder switches into operative relation with said lines.

5. The combination with a plurality of operators' positions divided into groups, of 80 means for extending calls thereto, a device associated with each operator's position actuated when the position is busy, apparatus for each group of positions controlled by said devices of the corresponding group 85 and operated when all of said devices are actuated, and means made operative in the operation of said apparatus for diverting calls from the associated group of positions.

6. The combination with a plurality of 90 operators' positions divided into groups, of means for extending calls thereto, said means normally acting to extend calls to one 95 of said groups, and means made active when all of the positions of said group are unavailable for causing said call extending means to direct calls to the operators' positions of another group.

7. The combination with a plurality of 100 telephone lines, of a plurality of finder 105 switches to the terminals of which said lines are multiplied, said finder switches being divided into groups, corresponding groups of operators' positions, circuits connecting said finder switches of each group with the operators' positions of the corresponding group, and means for making the finder 110 switches of one or another of said groups active to extend said lines to one or another of said groups of operators' positions.

8. The combination with a plurality of telephone lines, of a plurality of operators' 115 positions divided into groups, a corresponding plurality of groups of finder switches for extending the connections of calling lines to the corresponding groups of operators' positions, one of said groups of finder switches being normally active, an operator's selecting circuit common to the operators' positions of each group, and means responsive to an abnormal condition of said common operator's selecting circuit of said group for causing another group of finder switches to become active.

9. The combination with a plurality of 125 operators' positions divided into groups, of means for extending calls thereto, an operator's selecting circuit common to the operators' positions of each group, and means responsive to an abnormal condition of said 130

operator's selecting circuit of any group for causing said call-extending means to divert calls from said positions.

10. The combination with a plurality of 5 operators' positions divided into groups, of a corresponding plurality of groups of circuits for extending calls thereto, a circuit common to the call-extending circuits of each group, and means responsive to an ab- 10 normal condition of said common circuit of each group of positions for diverting calls from the group of circuits corresponding to said group of positions.

11. The combination with a plurality of 15 operators' positions divided into groups, of a corresponding plurality of groups of circuits, each of said groups serving to extend calls to the associated group of operators' positions, a switch at each operator's position 20 operated when the operator is attending to a connection, and means responsive to the coincident operation of said switches at all operators' positions of a group for diverting calls from the said associated circuits of that 25 group.

12. The combination with a plurality of operators' positions divided into groups, of a corresponding plurality of groups of circuits, each of said groups serving to extend 30 calls to the associated group of operators' positions, a switch at each operator's position operated when the corresponding position is vacant, and means responsive to the coincident operation of all of said switches 35 in a particular group of operators' positions for diverting calls from the aforesaid group of circuits leading to said group of positions.

13. The combination with a plurality of operators' positions divided into groups, of 40 a corresponding plurality of groups of circuits, each of said groups of circuits serving to extend calls to the corresponding group of operators' positions, a plurality of connecting circuits at each operator's position, 45 switching mechanism associated with each operator's position operated when all of the connecting circuits of the corresponding position are in use, and means responsive to the coincident operation of all of said 50 switching mechanisms of a particular group of operators' positions for diverting calls from the aforesaid circuits leading to the associated group of positions.

14. The combination with a group of operators' positions, of a group of circuits for 55 extending calls thereto, and means made operative when the group of positions to which said circuits extend becomes unavailable for handling calls to bar calls from the 60 circuits of said group.

15. The combination with a plurality of telephone lines, of two groups of operators' positions, a manual switch for making either of said groups of positions the preferred 65 group with respect to the extension thereto

of calls from said telephone lines, and an automatic switch under the control of the preferred group and adapted when operated to divert calls from said preferred group and direct them to the other or alternate 70 group.

16. The combination with a group of telephone lines, of two groups of finder switches for making connection therewith, means for moving the switches of each group, starting means under the control of any of said telephone lines in calling for controlling said moving means and starting a finder switch, a throw-over switch for bringing said starting means into operative relation 80 with the moving means of one or the other of said groups, and means made operative while said starting means is actuated for preventing the movement of said throw-over switch. 85

17. The combination with a plurality of telephone lines, of two groups of circuits for making connection therewith, a throw-over switch for bringing said lines into operative relation with one or the other of 90 said groups of circuits, an electromagnetic switch responsive to the initiation of a call by any of said lines for rendering operative one of the circuits in the group with which the lines are at the time in operative relation, and means controlled by said electromagnetic switch in its operation for preventing the movement of said throw-over switch. 95

18. The combination with a plurality of 100 telephone lines, of two groups of circuits for extending calls from said lines, said lines being normally in operative relation with one of said groups of circuits, and means made operative when said group becomes 105 unavailable to extend connections for bringing the other group into operative relation with said lines.

19. The combination with a plurality of 110 telephone lines, of two groups of circuits for extending calls from said lines, said lines being normally in operative relation with one of said groups of circuits, means made operative when said group becomes unavailable for extending connections for bringing 115 the other group into operative relation with said lines, an electromagnetic starting switch normally under the control of any of said lines in calling and through the medium of which the calling line exercises 120 control over one of the circuits of the group with which the lines are in operative relation, and means made operative when both of said groups of circuits become unavailable 125 for depriving said lines of control over said electromagnetic starting switch.

20. The combination with a plurality of 130 telephone lines, of a group of circuits for extending calls from said lines, an electromagnetic starting switch responsive to the

initiation of a call by any of said lines and through the medium of which the calling line exercises control over the circuits of said group, and means actuated when the circuits of said group become unavailable for depriving said lines of control over said electromagnetic starting switch.

21. The combination with a plurality of telephone lines, of a plurality of operators' positions divided into groups and serving the same lines, a corresponding plurality of groups of circuits each extending to an associated group of operators' positions, and automatic switching means for bringing calling telephone lines into operative relation with a group of circuits extending to a group of positions that is at the time available:

22. The combination with a plurality of telephone lines, divided into groups, of a group magnet associated with each group and actuated by any line of the associated group in calling, a group of circuits for extending calls from said lines, the selection of calling lines by said circuits being controlled by said group magnets, and means actuated when said group of call-extending circuits becomes unavailable for depriving said lines of control over said associated group magnets.

23. The combination with a plurality of telephone lines, of a plurality of groups of operators' positions, each operator's position of each group being provided with means for establishing connection with any of said telephone lines, and switching

mechanism for automatically selecting and directing calls to any of said groups of positions which is at the time available.

24. The combination with a plurality of telephone lines, of a plurality of groups of operators' positions, connecting circuits at each position of each group for completing connection with any of said lines, means for initiating calls for said telephone lines, automatic switching mechanism for directing an initiated call to a group of positions that is at the time available, means made active in the extension of a call in a particular group for directing the call to an unengaged position of that group, and means made active in the extension of the call to an unengaged position for selecting an idle connecting circuit of that position to complete the connection.

25. The combination with a plurality of telephone lines, of groups of switches for making connection to said lines, means for moving said switches, starting means for controlling said moving means and starting one of said switches, means for associating said starting means with the moving means of one or the other of said groups of switches, and means for preventing the operation of said associating means while said starting means is actuated.

In witness whereof, we hereunto subscribe our names this 11th day of November, A. D., 1916.

SAMUEL B. WILLIAMS, JR.
RALPH L. QUASS.
